UNITED STATES PATENT OFFICE.

JAMES A. MOORE, OF CENTRAL FALLS, RHODE ISLAND.

ADJUSTABLE FOOT-REST.

SPECIFICATION forming part of Letters Patent No. 634,582, dated October 10, 1899.

Application filed July 7, 1899. Serial No. 723,043. (No model.)

To all whom it may concern:

Be it known that I, JAMES A. MOORE, a citizen of the United States of America, and a resident of the city of Central Falls, in the county of Providence and State of Rhode Island, have invented certain new and useful Improvements in Adjustable Foot-Rests, of which the following is a specification:

My invention relates to an improved device in the nature of an adjustable foot-rest to be attached to a child's chair, an invalid's chair, go-carts, and any kind of vehicles or carriages in which persons may be conveyed or carried; and the objects of my improvement are, first, to provide a foot-rest that will adjust itself for the support and rest of the feet in whatever position they may be placed upon it, especially in the case of children and invalids, and, second, to provide a foot-rest that will offer but slight resistance, shock, or jar to the feet when they strike against it, (the foot-rest,) especially in the case of children and invalids, more especially children when placed in a high chair. I attain these objects by the construction, combination, and working of the parts, as illustrated in the accompanying drawings, in which—

Figure 1 represents a front elevation of a child's chair, showing my invention attached thereon. Fig. 2 is a side view of the same. Fig. 3 is a front elevation of one of the supporting members for the footboard. Fig. 4 is a side elevation of the same. Fig. 5 is an enlarged cross-sectional view taken in line X X of Fig. 1.

Similar letters of reference correspond to like parts in the drawings.

The footboard A, the supporting members a, the coiled-wire spring s, the metal chain c, the screws c', and the rubber bunters p, as shown in Fig. 5, constitute the framework of my invention, (adjustable foot-rest.)

a in Fig. 1 is one of the supporting members of my invention. r is the rounded end of such member. o represents the holes or perforations in rib a' of such member, as appears in Fig. 4. f is the flange of such member. c is the metal chain in Figs. 1, 2, and 5. s is the coiled-wire spring. c' c' are the metal screws which fasten and secure chain c to footboard A and front part of frame B of the chair.

My invention is constructed as follows:

Attach base of flange f of one of the supporting members a in Figs. 3 and 4 to the under part of footboard A by means of metal screws, as appears in Fig. 5, and pass one end of spring s through the holes o nearest the rounded end r of the supporting member a, and keep turning the spring s, so that said end of spring s will pass through each successive hole o in a' and around a, as in Fig. 5, and until said end meets a' near flange f. Then pass the opposite end of said wire spring s through holes o nearest the rounded end r of another supporting member a, and turn said member a so that said end of wire spring s shall pass through all the holes o in a' of such member and rounded end r comes in contact with and meets rounded end r of the first-mentioned supporting member a, as in Fig. 5, and said last-mentioned end of wire spring s meets a' and flange f of the second-mentioned supporting member. In like manner make another combination of two supporting members a with wire spring s, which holds them (said members) together. Secure the base of flange f of one of the supporting members secured and held together by wire spring s to footboard A—that is, to the under part of footboard A—by means of screws, as in Fig. 5, and in like manner fasten another combination of two supporting members held together by wire spring s, as in Fig. 5. To the rear part of footboard A fasten one end of chain c with screw c'. Insert rubber bunters p in recesses countersunk in front part of frame B of the front part of the chair, as appears in Fig. 5. Then attach the invention to front part of frame B of the chair—first, the bases of the flanges f to frame B by means of screws, as in Fig. 5, and, second, the opposite end of chain c to frame B by screw c'.

This is a complete and detailed description of the construction of my invention, of the several parts of the same, and the attachment and application of the same to the front part of a child's chair, as appears in Fig. 1.

The operation or working of my invention is shown in Fig. 5, where it may be seen that when the feet are placed upon footboard A in a certain way the foot-rest will rock or incline forward, as indicated by A in Fig. 5, and when the feet are taken off footboard A the coiled-wire spring s readjusts the foot-

rest, forcing or throwing back the foot-rest, the footboard A sometimes striking against the rubber bunters *p*. When the feet are resting upon the footboard A in any particular place or way, the foot-rest will adjust itself to support the feet in a most natural and easy manner. The foot-rest will move forward or backward, depending upon where the feet are placed upon the footboard A. 10 The chain *c* limits the extent to which the foot-rest can rock or move forward, as indicated by *A* in Fig. 5. The chain *c* also prevents the foot-rest from being pulled off by a child or forced off by the feet of a person. 15 What I claim as my invention, and desire to secure by Letters Patent, is— The herein-described foot-rest consisting of the combination of the footboard A, the

supporting members *a a* having a projecting flange *f* formed on one end thereof, the opposite adjoining ends of said members having rounded surfaces, each of said members having a vertical rib *a'* provided with a series of perforations, the coil-spring *s* passing through said perforations and surrounding both of 25 said members, with means for securing each top and bottom member to the footboard and frame of the chair, and the chain *c* with means for connecting the footboard and frame of the chair respectively, as shown and described. 30

Signed by me at Pawtucket, Rhode Island, this 3d day of July, 1899.

JAMES A. MOORE.
